Primary Examiner — Sandra Snapp

(57) **CLAIM**

The ornamental design for a massage therapy tool, as shown and described.

DESCRIPTION

FIG. 1 is a front view of a first embodiment of a massage therapy tool, the rear view being a mirror image thereof; FIG. 2 is a front view of a second embodiment of a massage therapy tool, the rear view being a mirror image thereof; and, FIG. 3 is a front view of a third embodiment of a massage therapy tool, the rear view being a mirror image thereof. Each of my three (3) massage therapy tool are characterized by a tubular member attached to a handle with each unit having diversely crafted tips.

1 Claim, 3 Drawing Sheets Fig. 1
